Primary Examiner — Philip S Hyder(74) *Attorney, Agent, or Firm* — Stinson Leonard Street LLP(57) **CLAIM**

The ornamental design for pole sander, as shown and described.

DESCRIPTION

FIG. 1 is a front perspective of a pole sander of our new design, the precise length of a pole of the pole sander is not claimed;

FIG. 2 is a rear perspective of the pole sander;

FIG. 3 is a front elevation of the pole sander;

FIG. 4 is a top plan view of the pole sander;

FIG. 5 is a right side elevation view of the pole sander;

FIG. 6 is a rear elevation view of the pole sander;

FIG. 7 is a bottom plan of the pole sander; and,

FIG. 8 is a left side elevation of the pole sander.
